ATTORNEY.

UNITED STATES PATENT OFFICE.

ARTHUR E. SHAW, OF PHILADELPHIA, PENNSYLVANIA, ASSIGNOR TO THE PENNSYLVANIA GLOBE GAS LIGHT COMPANY OF PHILADELPHIA, OF PHILADELPHIA, PENNSYLVANIA, A CORPORATION OF PENNSYLVANIA.

STREET-LIGHT SIGN-HOLDER.

No. 914,195.

Specification of Letters Patent.

Patented March 2, 1909.

Application filed July 24, 1907. Serial No. 385,305.

To all whom it may concern:

Be it known that I, ARTHUR E. SHAW, a citizen of the United States, and a resident of Philadelphia, in the county of Philadelphia and State of Pennsylvania, have invented a certain new and useful Street-Light Sign-Holder, of which the following is a specification.

Objects of the present invention are to provide a satisfactory holder which will accommodate signs of the same or slightly different lengths and to which the signs may be easily and conveniently applied and removed; and to prevent the signs from rattling in the holder.

To these and other ends hereinafter set forth the invention comprises the improvements to be presently described and finally claimed.

The nature, characteristic features and scope of my invention will be more fully understood from the following description taken in connection with the accompanying drawings forming part hereof and in which—

Figure 1, is a perspective view looking down upon a sign holder embodying features of the invention and showing portions of two signs. Fig. 2, is a similar view with the signs removed looking inward and upward at the sign holder. Fig. 3, is a transverse, sectional view. Fig. 4, is a perspective view illustrating a sign holder embodying a modification of the invention, and Fig. 5, is a view illustrating the sign holder shown in Fig. 4, with the heads of the screws removed.

In the drawings 1, is a body provided with faces 2, and 3, arranged at an inclination, shown as a right angle, in respect to each other. At the apex of these faces is arranged a stop 4, upon the sides of which the ends of the sign may abut. This body is also provided with shelves 5, upon which the lower edges of the ends of the signs rest, and it may be provided at the top with similar shelves 7, which when present overlie the top edges of the signs.

10, is a cover plate bent to form a plane face 11, having wings 12 and 13 projecting at an angle from it. This cover plate overlies the ends of the signs *a*, and *b*, and it is provided with openings which coöperate with screws 16 and 17 projecting from the body. The cover 10, is therefore detachable in respect to the body. In Fig. 2, *c*, is one of the 55 pockets for the reception of the end of a sign.

As shown in Figs. 4, and 5, two cover plates 16^a, each having two open ended slots 17^a and 18, are employed and four screws 19, are employed instead of two. This construction is substantially the same as has 60 been described with the exception that it is possible to remove one sign without taking the cover plate from in front of the adjoining sign.

In its rear the body 1, is provided with a 65 spring 20, the ends of which bear upon the signs *a*, and *b*, and by exerting a gentle pressure upon them, they hold the signs in contact with the inner faces of the cover plate, so that the signs may not rattle. The spring 70 20, is shown as secured to the body 1, by means of a screw 21 which is inserted into the rear of the body, or more accurately, into a projection formed thereon.

The top of the body is provided with a 75 V-shaped projection 22, and the under-face of the arm 23, is provided with a corresponding V-shaped projection 23^a and these projections by engaging each other and when the screw 24 is in place, secure a firm, rigid 80 and properly aligned connection between the arm and the body.

What I claim is:

1. In a sign holder the combination of a body having faces arranged at an inclination 85 with respect to each other and provided at one end with a generally V-shaped projection, a supporting arm overlying the other end of the body and provided with a corresponding V-shaped projection, and means for securing 90 the arm and body together, substantially as described.

2. In a sign holder the combination of a holder provided with a pocket, a sign having its end arranged in the pocket, and a spring 95 projecting from the holder and adapted to bear upon the sign and press it down upon one wall of the pocket, substantially as described.

3. A sign holder comprising a body provided with angularly disposed faces and with a stop arranged between the faces and with shelves at the ends of the faces, a cover plate adapted to overlie the faces, and means for detachably connecting the body and 100 cover plate, substantially as described.

4. A sign holder comprising a body provided with faces arranged at an inclination to each other and with a stop between the faces and with ledges arranged at the ends of 110

the faces, screws projecting from the body and a detachable cover plate provided with openings adapted to coöperate with the screws, substantially as described.

5. A sign holder comprising a body having angularly disposed faces provided with end shelves, screws projecting from the body, and a detachable cover plate provided with

open ended slots adapted to coöperate with the screws, substantially as described. 10

In testimony whereof I have hereunto signed my name in the presence of witnesses.

ARTHUR E. SHAW.
